UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

CONTROLLING-SWITCH.

1,333,501.

Specification of Letters Patent. Patented Mar. 9, 1920.

Application filed December 10, 1918. Serial No. 266,067.

To all whom it may concern:

Be it known that I, DANIEL J. McCARTHY, a citizen of the United States, residing at Elgin, in the county of Cook and State of Illinois, have invented certain new and useful Improvements in Controlling-Switches, of which the following is a specification.

My invention relates to a controlling switch, and more particularly to a track box switch for electrically actuated railway signaling apparatus.

The primary objects of the invention are: to provide a switch which will be simple and economical in construction; to provide arrangements of the switch contacts and of the actuating mechanism for making and breaking the circuits controlled by the device whereby the actuation of the switch mechanism will be effected with accuracy by a movement of an actuating lever of small amplitude; to provide a device comprising a rocking member for carrying the movable contact or contacts which has a single bearing and is rocked in both directions by a cam on the actuating shaft of the switch mechanism, thus eliminating springs, links, or other connecting members which involve a multiplicity of bearings and through wear or faulty adjustment are likely to give occasion for lost motion and uncertainty in operation; to provide a simple device whereby the contact or contacts may be conveniently removed from the rocking member when necessary, to provide means for protecting the contacts from injury by condensation dripping from the track box or casing which incloses the mechanism; and to provide other incidental improvements in the construction of the switch and track box to be hereinafter described and claimed.

The invention is illustrated, in a preferred embodiment, in the accompanying drawings, wherein:

Figure 1 is a sectional view taken through the track box showing the switch mechanism partly in section and partly in elevation;

Fig. 2 is a fragmentary sectional view of the switch mechanism, and adjacent parts of the box, this view being taken on line 2—2 of Fig. 3, but on a larger scale;

Fig. 3 is a broken plan view of the switch box;

Figs. 4 and 5 are sectional views on lines 4—4 and 5—5, respectively, of Fig. 1, looking in the direction of the arrows, the operating shaft in Fig. 5 being shown in elevation;

Fig. 6 is a sectional plan taken through the cam and rocking shafts, and associated parts, with certain of said parts shown in elevation for the purpose of clearness; said views being taken on line 6—6 of Fig. 2;

Fig. 7 is a fragmentary sectional view, taken on line 7—7 of Fig. 3, illustrating a preferred form of device for limiting the movement of the operating shaft; and

Fig. 8 is a fragmentary view in elevation, showing the preferred manner of securing the operating crank to one end of the operating shaft.

Like characters of reference designate like parts in the several figures of the drawings.

Referring to the drawings, 25 is a metal box having perforated ears 26 for securing it to railroad ties or other suitable supports. 27 is the cover of the box which is hinged to the box at 28 and has a padlock eyelet 29 adapted to be engaged by a hasp 30 hinged at 31 to a nut 32 engaging the threaded end of a rod 33 which is pivoted at its other end to a clevis 34 on the end of the box. The nut 32 is adapted to bear upon a forked lug 35 on the cover 27. The cover may be given a close fit on the box by screwing the nut 32 down against lug 35 before the hasp is turned to engage the padlock eyelet 29. Preferably, the cover is formed with a four-sided rib 36 grooved for a resilient gasket 37 which bears upon the edges of the box, on three sides thereof, and upon a rib 38 formed along the upper edge of the contact supporting block 39 of insulating material, and this gasket provides sufficient resiliency to insure close engagement of the cover on the box. The insulating block 39 is secured by bolts 40 to a web 41 projecting upwardly from the bottom of the box.

Ordinarily there will be several controlling switches in each track box, all operated from a single shaft which is rocked when the switch point with which the track box is

associated is moved. These controlling units are all alike and but one need be described. In the arrangement shown the unit comprises two fixed contacts, a front contact 42, and a rear contact 43, which are secured to the insulating block 39 by binding posts 44, 45, respectively. 46 is a binding post for a wire 47 extending to the movable front and back contacts 48, 49, which are adapted to 10 coöperate with contacts 42, 43, respectively. The movable contacts 48, 49, are springs and are secured to an upwardly projecting nose piece 50 formed on a metal plate 51 which is removably secured to the under side of an 15 insulating block 52 by means of bolts 53. The insulating block 52 is attached by bolts 54 to a rocking member 55 having an arm 56 provided with a hub 57 for mounting the member revolubly on a shaft 58. The forward 20 end of arm 56 carries a roller 59 and a similar roller 60 is mounted in a bifurcated lug 61 on the rocking member 55. The rollers 59, 60 are adapted to bear against a cam ring 62 which is fixed to a rock shaft 63 adapted to be operated by a lever 64. The 25 shaft 62 projects from the box on opposite sides and the lever 64 may be attached to either end of the shaft as may be most convenient, in accordance with the position of the box with respect to the track. The cam ring 62 is formed with a cam 65 (and preferably with another cam 66 which comes into play when the switch is used in connection with a three-position signal). The circumferential dimension of cam 65 is such that when one of the rollers 59 or 60 is at the 30 extreme end of the cam the other roller bears on the cam ring at a point closely adjacent the cam. A very slight angular movement of the rock shaft will, therefore, cause 35 one roller to ride down from the cam upon the narrowest part of the cam ring and the other roller to ride up from the ring upon the cam. The rotational movement of the 40 cam produces a rocking movement of the structure carrying contacts 48 and 49 which breaks the circuit controlled by one of the contacts and closes the circuit controlled by the other. For both positions of rest of the 45 rocking member both contact springs are flexed. In the position of the parts shown in Figs. 1 and 2, the front contact spring 48 is flexed against the fixed contact 42 while the back contact spring 49 is flexed 50 against a relatively rigid finger 67 which is secured to the projection 50 on the rocking member. A similar finger 68 is arranged on the opposite side of spring 48. When the rocking member is moved to its other 55 position contact spring 48 remains in contact with the fixed contact 42 until separated therefrom by the rigid finger 68. Contact spring 49 is brought to bear against the fixed contact 43 before the rocking member 60 reaches the limit of its angular movement. 65

The continued angular movement of the rocking member withdraws finger 67 from contact spring 49. The contact springs and fingers are so disposed that the making of one circuit takes place immediately after 70 the breaking of the other. By these arrangements of the circuit making and breaking devices and by the construction of actuating mechanism for shifting the movable contacts so as to minimize lost motion, a controlling switch is provided which will be accurate and positive in its operation, without requiring adjustments and repair, even where the angular movement of the controlling shaft, shaft 63, is small. This is an important 75 consideration in a track box controller which is operated by a switch point rail, the extent of movement of which is slight. 80

It is important that the cam ring 62 be 85 capable of a minute, circumferential adjustment on the shaft 63. The device employed for effecting this adjustment is preferably that disclosed in my co-pending application Serial No. 251,250, filed August 24, 1918. The cam ring 62 is arranged on a disk 69 having hubs, secured to, preferably driven upon the shaft 63, the edges of which are beveled off, as shown at 63^a. When a plurality of disks 69 are secured to the shaft 90 63, the hubs of the disks abut against each other so as to provide spacing elements which hold the cams in spaced relation with each other. The edge of the disk is provided with a retaining flange 70 for one 95 side of the cam and an adjusting ring 71 bearing against the other side of the cam ring. The surface 72 of the disk 69 is formed with recesses 73 which are shallow at the middle and are made deeper at their 100 extremities, the bottom of the recess being substantially V-shaped in section, as shown in Fig. 2. In each of these recesses are arranged, on opposite sides of the high point at the center, a pair of clutch rollers 74 105 pressed toward each other by springs 75. These rollers are capable of wedging engagement between the cam ring 62 and the shallow end of the recesses 73 and act as a clutch to prevent relative turning. The adjusting plate 71 is supported in proper position by set screws 76 which extend through slots 77 in the plate. Clearance is provided between the screw head and the plate so that the plate may be rotated slightly by 110 means of its handle 78. The plate carries a plurality of studs 79 corresponding in number to the pairs of clutch rollers 74, a stud extending between each pair of such rollers. The rotation of the adjusting plate 115 will force one clutch roller of each pair back into the widened end of its recess so as to allow the rotational adjustment of the cam ring in the opposite direction of such roller. When this adjustment has been 120 125 130

made the adjusting ring 71 may be turned back so as to put the studs 79 in their original position by means of the pressure of the spring 75 against the studs.

5 The rocking members of the several units are all mounted on shaft 58 with their hubs 57 bearing on each other, end to end. Shaft 58 is supported on bosses 80, 81, on the inner sides of the box and the shaft being held in 10 place by set screws 82 in boss 80. The shaft is put into place through a perforation 83 in the side of the box, this opening being closed afterward by a plug 84.

15 The rock shaft 63 is supported at opposite ends by bushings 85, 86, which are preferably driven upon the shaft so as to rotate therewith. These bushings extend through bosses 87, 88, on the box 25 and provide 20 bearings for the rock shaft 63. The inner ends of the bushings 85, 86 are formed with flanges which bear against the inner faces of the bosses 87, 88. These flanges are cut away, as indicated at 89 (Fig. 7) to provide 25 lugs 90, 91 which engage stops 92, 92 when the shaft 63 is rocked a predetermined distance in either direction. The stop consists preferably of bolts 93 which extend through holes in the bosses 87, 88.

30 The operating arm 64 is formed with a squared opening adapted to fit over either end of the shaft 63, and is slit as indicated at 94. A clamping bolt 95 extends through the inner end of the arm 64 which when tightened clamps the arm firmly on the 35 shaft. The shank of this bolt fits in a groove 96 formed in the shaft 63, so as to prevent any lateral movement of the arm, and keeps the arm in perfect alinement with the rod connecting it with the switch. 64^a is a 40 washer which fits over the opposite end of the shaft 63 which projects out of the track box.

45 The switch boxes are ordinarily made of cast iron and considerable inconvenience has been experienced through the condensation of moisture on the under sides of the covers of the boxes and the dripping of this condensation upon the electrical contacts of the switch mechanism. To prevent this I 50 provide a shield plate 97 which extends across the box from side to side above the contacts. This shield plate is pivoted to the sides of the box by pivots 98 extending through flanges 99 formed on the end of the 55 shield plate. These flanges are notched at the ends opposite to the pivots as indicated at 100, for engagement with studs 101 on the box. The shield plate may be raised to give access to the contacts but before the 60 cover plate of the box can be put in place the shield plate must be folded down to horizontal position.

65 It will be seen that the switch mechanism of my invention is extremely simple in its construction and positive in its operation.

The compactness of the mechanism allows it to be closed in a box which will not extend above the upper surface of the rail when the box is located on the ties supporting such rail. The actuating mechanism of 70 the switch employs no springs or links or toggles. The rocking member is mounted on a single shaft, the wear upon which will be comparatively slight due to the small angular movement of the rocking member. 75 The possibility of developing lost motion through wear of the parts is reduced to a minimum. The arrangement of the contacts is such that a slight angular movement of the rocking member 55 carrying the movable contacts will open one of the controlled 80 circuits and close the other.

I claim:

1. In an electric current controller, the combination of a rocking member, a contact 85 element carried thereby, another contact element against which the aforesaid element is adapted to bear, and a revoluble cam which bears against the rocking member at two separated points for rocking said member 90 positively in both directions.

2. In an electric current controller, the combination of a rocking member, a contact 95 element carried thereby, another contact element against which the aforesaid element is adapted to bear, a revoluble cam ring formed with a cam, and a pair of rollers on the rocking member adapted to bear upon said cam ring and cam, arranged so that they engage the cam one at a time. 100

3. In an electric current controller, the combination of a rocking member, a contact element carried thereby, another contact element against which the aforesaid element is adapted to bear, a rock shaft 105 adapted to be moved by a switch point, a disk fixed to said shaft, a cam adapted to engage said rocking member to move the same positively in both directions, and means for adjustably securing said cam to 110 said disk.

4. In an electric current controller, the combination of a rocking member provided with a pair of rollers, a contact element carried by the rocking member, and a revolubly 115 supported cam ring against which both rollers bear at different distances from the center of movement thereof.

5. In an electric current controller, the combination of a rocking member provided 120 with a pair of rollers, a contact element carried by the rocking member, a rock shaft adapted to be moved by a switch point, and a cam ring fixed to said shaft with which both rollers bear at different distances from 125 its center of movement.

6. In an electric current controller, the combination of a shaft, a rocking member mounted on the shaft provided with contact 130 supporting means on one side of the shaft.

and an arm projecting on the other side thereof provided with a roller, a rock shaft, a cam ring fixed thereto with capacity for circumferential adjustment thereon, and another roller on the rocking member adapted to bear on said cam ring.

7. In an electric current controller, the combination with a rocking member and means for rocking the same, of an insulating block secured to said member, a contact carrier removably secured to the under side of said block and having a projection at one side of said block, and a contact spring secured to said projection.

15 8. In an electric current controller, the combination with a rocking member and means for rocking the same, of an insulating block secured to said member, a contact carrier removably secured to the under side of said block and having a projection at one side of said block, and a pair of contact springs secured to opposite sides of said projection.

9. In an electric current controller, the combination with a rock member and means for rocking the same, of an insulating block secured to said member, a contact carrier removably secured to said block and having a projection at one side of said block, a pair of fixed contacts, a pair of spring contacts secured to said projection so as to extend between the fixed contacts, and a pair of rigid fingers secured to said projection on opposite sides of said spring contacts.

35 10. In an electric current controller, the combination with a fixed contact, of a rocking member, mechanism for rocking the same, an insulating block secured to said rocking member, a plate arranged on the under side of said block, fastening devices extending through the block from the top for holding said plate in position, an upwardly and outwardly extending projection on said plate, a spring contact member, and means for securing the same to said projection.

11. In an electric current controller, the combination with a fixed contact, of a rocking member, mechanism for rocking the same, an insulating block secured to said rocking member, a plate arranged on the under side of said block, fastening devices extending through the block from the top for holding said plate in position, an upwardly and outwardly extending projection on said plate, a spring contact member, a rigid finger for forcing said spring contact member away from the fixed contact, and means for securing said spring contact and finger to said projection.

60 12. In an electric current controller, the combination with a pair of fixed contacts, of a rocking member, mechanism for rocking the same, an insulating block secured to said rocking member, a plate arranged on the un-

der side of said block, fastening devices extending through the block from the top for holding said plate in position, an upwardly and outwardly extending projection on said plate, a pair of spring contacts adapted to engage with said fixed contacts, respectively, a pair of rigid fingers adapted to force said spring contacts from their respective fixed contacts, and means for securing said fingers and spring contacts to said projection. 75

13. In an electric current controller, the combination with a rocking member and mechanism for rocking the same, of a fixed contact, a spring contact on the rocking member adapted to be flexed against the fixed contact, and a rigid circuit breaking finger on the rocking member adapted to bear against the spring contact and separate it from the fixed contact and flex the spring in the opposite direction. 80

14. In an electric current controller, the combination with a rocking member and mechanism for rocking the same, of a pair of oppositely arranged fixed contacts, a pair of spring contacts on the rocking member 90 adapted to be flexed against said fixed contacts respectively, and a pair of rigid circuit breaking fingers on the rocking member adapted to be brought to bear against the spring contacts, respectively, to separate 95 them from their fixed contacts and flex them in opposite directions.

15. In a track box circuit controller, the combination with a box, of a rock shaft mounted in the box and adapted to be rocked by a switch point, a rocking member in said box, a cam on said shaft for moving said rocking member positively in opposite directions, a fixed contact, a spring contact on the rocking member adapted to be flexed 100 against the fixed contact, and a rigid circuit breaking finger on the rocking member adapted to be brought to bear against the spring contact to separate it from the fixed contact and flex it in the opposite direction. 110

16. In a track box circuit controller, the combination with a box, of a rock shaft mounted in the box and adapted to be rocked by a switch point, a rocking member in said box, a cam on said shaft for moving said 115 rocking member positively in opposite directions, a pair of oppositely arranged fixed contacts, a pair of spring contacts on the rocking member adapted to be flexed against said fixed contacts, respectively, and a pair 120 of rigid circuit breaking fingers on the rocking member adapted to be brought to bear against said spring contacts, respectively, and separate them from their fixed contacts and flex them in opposite directions. 125

17. In a track box circuit controller, the combination with a box, of a rock shaft mounted in the box and adapted to be rocked by a switch point, a rocking member in said box, a cam on said shaft for moving said 130

rocking member positively in opposite directions, a pair of oppositely arranged fixed contacts, a pair of spring contacts on the rocking member adapted to be flexed against 5 said fixed contacts, respectively, a pair of rigid circuit breaking fingers on the rocking member adapted to be brought to bear against said spring contacts, respectively, and separate them from their fixed contacts 10 and flex them in opposite directions, and means for adjusting said cam circumferentially with respect to the rock shaft.

18. The combination with a track box having a cover over the top of the same and a 15 switch mechanism therein comprising fixed and movable contacts; of a shield plate arranged over said contacts pivoted at one end to the box directly under the cover thereof, and means for supporting the other end of 20 said plate.

19. In an electric current controller, the combination with a plurality of rocking members and contacts carried by said members, of means for rocking said members 25 comprising a shaft, cams secured on said shaft, and provided with spacing hubs, and an operating arm connected to said shaft and adapted to be operatively connected with a switch.

30 20. In an electric current controller, the combination with a plurality of rocking members formed with spacing hubs, contacts carried by said members, means for rocking said members comprising a rock shaft, and 35 a plurality of cams capable of circumferential adjustment and formed with spacing hubs secured to said rock shaft.

21. In an electric current controller, the combination with a rocking member, of a 40 contact member carried by said rocking member and adapted to have a limited movement, of means for rocking said member comprising a rock shaft, a cam on said shaft adapted to engage said member at two 45 points, and means providing a stop for said shaft whereby its movement may be limited.

22. In an electric current controller, the combination with a casing, of a rocking member in the casing, a contact member 50 carried by the rocking member and adapted to have a limited movement, means for rocking said member comprising a shaft, and a cam on said shaft adapted to engage said rocking member, and means for limiting 55 the movement of the rock shaft comprising a bushing secured to the shaft to provide a bearing and provided with a flange which is cut away to provide stops which engage a projection on said casing.

60 23. In an electric current controller, the combination with a casing, of a rocking member in the casing, a contact member carried by the rocking member and adapted to have a limited movement, means for rock- 65 ing said member comprising a square shaft,

a cam on said shaft adapted to engage said rocking member, and means for limiting the movement of the rock shaft comprising a cylindrical bushing secured to the shaft to provide a bearing and provided with a 70 flange which is cut away to provide stops which engage a projection on said casing.

24. In an electric switch, the combination of circuit making and breaking mechanism comprising two elements, one of 75 which is rotatable upon the other and which are formed to provide recesses between the elements tapering in depth toward each other, a revoluble clutch member in each of said recesses, and means for forcing one of 80 said members into the deep end of its recess to permit the adjustment rotationally of one element on the other.

25. In an electric switch, the combination of a revoluble actuating element, a circuit 85 controlling element mounted thereon with capacity for rotational adjustment and means for providing an adjustable engagement between said revoluble element and circuit controlling element comprising a 90 pair of spring pressed, revoluble clutch members between said elements oppositely arranged so that one operates to oppose relative movement between the elements in one direction and the other in the other direction, and a device rotatably mounted on one 95 of said elements adapted, by its movement in one direction or the other, to engage one of the clutch members and move it to an inoperative position.

100 26. In an electric switch, the combination of a revoluble actuating element, a circuit controlling element mounted thereon with capacity for rotational adjustment and means for providing an adjustable engagement between said revoluble element and circuit controlling element, comprising a 105 pair of spring pressed, revoluble clutch members between said elements oppositely arranged so that one operates to oppose relative movement between the elements in one direction and the other in the other direction, a device rotatably mounted on one of said elements adapted, by its movement in one direction or the other, to engage one of 110 the clutch members and move it to an inoperative position, and means for fixing said rotatable device to the element which it engages.

115 27. In an electric switch, the combination 120 of a fixed contact, a movable contact, an actuating shaft, a cam associated with the shaft, a cam actuated device connected with the movable contact and adapted to move said movable contact into and out of engagement with said fixed contact, means for 125 adjusting the position, rotationally, of the cam on the shaft comprising a disk keyed to the shaft and formed with a recess which increases in depth toward its ends from a 130

- 6
- point of minimum depth, a pair of rollers in the opposite ends of said recess, springs to press the rollers toward the shallow portion of the recess, a plate rotatably engaged with the disk provided with a stud adapted to bear against one or other of said rollers in accordance with the direction in which the plate is rotated, and means for fixing said plate to the disk.
- 10 28. In an electric switch, the combination with a pair of oppositely arranged contacts, a movable contact disposed between the first named contacts, a revolute, eccentrically formed member for moving said last-named contact, an actuating shaft on which said revolute member is supported, a disk fixed to the shaft and arranged between the shaft and the revolute member, said disk being formed with a recess increasing in depth
- 15 toward its ends from a point of minimum depth, rollers in said recess, springs to force said rollers toward the shallow part of the recess, and a plate rotatably engaged with said disk, and having means for fixing it thereto provided with a stud which is adapted, when the plate is rotated, to engage one or other of said rollers to force the same into the deep end of its recess.
- 20 29. An electric current switch, comprising a cam controlled contact member, means for actuating the cam and a friction clutch for transmitting movement from said actuating means to the cam whereby said cam is capable of delicate adjustment with respect to said actuating means. 35
30. An electric current switch comprising a fixed and movable contact, means for moving said movable contact, an operating arm and a friction roller clutch for transmitting movement between said operating arm and said moving means whereby said moving means may be adjusted relative to said operating arm. 40
31. In an electric current switch, fixed and movable switch contacts, a cam for actuating the movable contact, a switch operating arm, a friction roller clutch for connecting said arm and cam whereby said cam may be adjusted relative to said arm to vary the time of actuation of said movable contact. 45 50
